UNITED STATES PATENT OFFICE.

CHARLES H. ASHLEY AND LEIGH H. PHILLEO, OF LOS ANGELES, CALIFORNIA.

TOWEL HOLDING AND DISPENSING CABINET.

Application filed March 17, 1926. Serial No. 95,428.

Our invention relates particularly to a cabinet adapted to hold and dispense hand towels one by one for use without wholly disconnecting the towel from the cabinet, each 5 towel being folded within the cabinet with a part attached to the cabinet and another part exposed to be pulled for the purpose of pulling the towel out of the cabinet for use.

Among the salient objects of this invention is to provide an improved means for holding the folded towels within the cabinet so that a quantity of towels will be held in folded condition therein and each can be pulled therefrom without pulling the others 15 with it.

In order to explain our invention, we have shown the same on the accompanying sheet of drawings, which we will now explain:

Figure 1 is a perspective view of a cabinet, 20 with a part of the front removed and a part of one end broken away to show the interior construction and arrangement;

Figure 2 is a fragmentary view of a cabinet, showing a slightly modified form of 25 mechanism for holding folded towels within the cabinet;

Figure 3 is a fragmentary view of a cabinet showing still another means of holding folded towels within the cabinet so that they 30 can be removed individually for use; and

Figure 4 is a fragmentary view showing one corner of a towel with tab.

Referring in detail to the drawings, the cabinet or case 1 is open at its bottom side 35 and is provided with a hinged front, 2, to give access to the interior thereof. A rod, 3, is inserted across the open bottom, and is held in place by being inserted through two depending ears, as 4, at the opposite ends of the cabinet, the rod having secured thereto a 40 plate, 5, corresponding to the ear 4, with slot, 6, therethrough, to receive a staple, 7, on the ear, 4, whereby a small padlock, 8, can be used to lock the rod in place across the open bottom of the case, as clearly shown. The cabinet 45 is provided with a series of partition members, as 9, 9, the lower, front corners of which rest upon a cross strip, 10, lengthwise of the case and positioned at the front of the bottom. The towels, T, are folded and placed 50 together between the partitions, 9, 9, as indicated and rest upon the cross strip, 10, as indicated in Fig. 1, each towel being provided with a tab, as 11, with eye, 12, therein, to receive the cross rod, 3, for holding it.

Each towel is also provided with a pull tab,

13, by means of which it can be pulled from the cabinet, as indicated in Fig. 1, wherein one towel is shown hanging from the rod, as left after it has been used.

Referring to Fig. 2, the cabinet is shown provided with movable partitions, 14, 14, on a rod 15, through the upper ends thereof, and on which are placed two springs, as 16, adapted to yieldingly move said partitions 60 apart on said rod, 15. The towels, T, are placed between the end of the cabinet and said partitions, or between pairs of partitions, with said partitions crowded together, so that as a towel is pulled, the springs force said 65 pairs of partitions apart and thus maintain a tension on said folded towels. The cabinet is also provided with a cross strip, 17, for supporting the lower side of the folded towels, as indicated. The partitions are provided on 70 their adjacent faces with recesses 14^a to receive the springs, 16, as indicated, whereby said partitions can be moved close together. The lower part of the cabinet is made similar to that shown in Fig. 1, and the towels 75 are provided with the attaching tabs and the pull tabs, as shown in Fig. 1, but not necessary to be shown again here.

In Fig. 3, another means for holding the towels is shown, and comprises flexible 80 straps, as 19, 19, secured to the top, 18, and each provided at its opposite ends with weight members, 20, 20, adapted to automatically press the towels placed therebetween and hold them by the action of gravity on 85 said weight members, or partitions, 20, 20. As the towels are pulled therefrom, said weight partitions move together, as will be 90 clear.

In Fig. 4, a fragmentary corner of a towel, 95 T, is shown with a loop, 21, of cord, instead of being a flat tab, as illustrated in the other cases, Fig. 1, and while any form of tab or pulling part can be provided, we do not limit our invention to any particular means for 100 pulling said towels from the cabinet in which they are held in folded form. Nor do we limit our invention to any particular type of cabinet or holding means therein for holding the towels in folded condition, except 105 as we may be limited by the hereto appended claims.

We claim:

1. A towel holding cabinet comprising a box with an open bottom and front and with 110 closed top, back and ends, a hinged door covering the front, a cross strip across the

bottom from one end to the other to support towels thereon and leaving the major portion of the bottom open, and a cross rod across the bottom from one end to the other 5 and detachably held in place, and adapted to have towels attached thereto, and means for locking said cross rod in place with open space adjacent one side thereof, whereby towels can be pulled from said cabinet 10 through the open bottom while attached to said cross rod.

2. A towel holding cabinet comprising a box with open bottom, a cross strip narrower than said open bottom across said 15 bottom from one end to the other to support

folded towels edgewise thereupon within said box, a cross rod across said open bottom near said cross strip from one end to the other, detachably held in place and adapted to have a part of each towel threaded thereon, whereby said towel can be pulled from said cross strip, through said open bottom with its part attached to said cross rod, and means for locking said cross rod in place. 20

Signed at Los Angeles, Los Angeles 25 County, California, this 12 day of March, 1926.
